[57] CLAIM

The ornamental design for a tendon hammer, substantially as shown.

DESCRIPTION

FIG. 1 is an elevational view partly from above of the tendon hammer with the telescopic handle collapsed; FIG. 2 is a side elevational view of the tendon hammer of FIG. 1;

FIG. 3 shows the end of the tendon hammer as seen in the direction II of FIG. 2;

FIG. 4 shows a side elevational view of the tendon hammer as seen in the direction III of FIG. 2, and

FIG. 5 shows an elevational view partly from below of the tendon hammer with the telescopic handle in its extended position.

*Fig. 1**Fig. 2**Fig. 3**Fig. 4**Fig.5*
